DESIGN FOR A GOLF GAME BOARD

Kenneth R. Quigley, Seattle, Wash.

Application January 19, 1942, Serial No. 105,290

Term of patent 14 years

To all whom it may concern:

Be it known that I, Kenneth R. Quigley, a citizen of the United States, residing at Seattle, in the county of King and State of Washington, have invented a new, original, and ornamental Design for a Golf Game Board, of which the following is a specification, reference being had to the accompanying drawing forming a part thereof.

In said drawing, the single figure is a top plan view of a golf game board showing my new design. Portions of the drawing are lined to indicate contrasting colors. The article is of no appreciable or substantial thickness.

I claim:

The ornamental design for a golf game board, as shown and described.

KENNETH R. QUIGLEY.
